GUSTAF ALBIN ROSE, OF JAMESTOWN, NEW YORK, ASSIGNOR TO DAHLSTROM METALLIC DOOR COMPANY, OF JAMESTOWN, NEW YORK, A CORPORATION OF NEW YORK

METHOD OF IMITATING WOOD GRAINING

Application filed August 31, 1929. Serial No. 389,855.

My invention relates to an improved method of producing imitation wood-graining effects on metallic and other hard surfaces.

The primary object of the invention is the production of a method which can be used in simulating the grain or pores of wood on concaved, convex and irregularly formed surfaces as readily as on flat surfaces.

In methods now in use for simulating wood graining on metallic or like surfaces, the "make-up" required to prepare the surface for final treatment, during which the wood pores of certain woods are simulated, necessitates the use of photographic negatives of the grain to be simulated, the different lights of which are reproduced on metal in the form of high and low regions; the low regions or parts being filled with paint which is transferred to the surface of the metal to receive the graining effect. Other similar more or less complicated and expensive methods are also employed, all of which make it impossible to simulate wood pores or graining on concave, convex or other curved surfaces; thus making it necessary to resort to hand graining of such parts, requiring the services of skilled and expensive artisans to match the effect produced in the adjacent flat regions under the method employed. This results in easily discernible breaks or irregularities in the finished work, since it is found extremely difficult to produce, under hand graining, the finer grain lines so essential to a perfect simulation of wood graining.

It is the purpose of my invention to enable unskilled labor to simulate wood grains or pores, of most kinds of wood, under my improved method, as readily and effectively as can be produced by skilled artisans and to enable any skilled artisan to simulate the more complex graining of certain kinds of wood more expeditiously, and at less cost than any method known to me, and also to assure perfect simulation of wood grains under such conditions on all kinds of metallic or like surfaces.

A further object of my invention is to dispense with the expensive photographic and engraving requirements forming part

of present day methods of simulating wood graining on metallic and like surfaces; and to provide a method for this purpose which is inexpensive and quickly accomplished and which will result in a decided reduction in the price of the product resulting from the use of this method.

With the above and other objects in view, my invention consists in the new and novel method of simulating wood pores or grains on metallic or other hard surfaces; and in the novel steps employed in my improved method, all as hereinafter described and more particularly set out in the appended claims.

In the drawing:

Fig. 1 is a perspective view of a sheet-metal article of construction, prepared with a coat of priming paint to provide the proper color or ground for the graining to be applied thereto under my improved method; the article shown having flat and convex surface portions.

Fig. 2 is a similar view showing the article of construction partly treated under the next step in my improved method; a pressure spray-gun being shown in the act of stippling the colored or ground-covered surface of the article.

Fig. 3 is a similar view showing the article of construction stippled and part of the previously stippled surface brushed out to form wood pores or grain under action of a brush capable of being moved into, over, or along curved or irregular as well as flat surface portions.

In practicing my invention, I employ simple and easily performed steps, such as can, in most cases, be easily exercised by persons unskilled in the art and of average intelligence.

The steps of my improved method are illustrated in the accompanying drawing to depict one of several ways under which such steps may be performed. For this purpose I have illustrated a simple article of construction which represents a part of metallic trim of a building, a railway car, or an automobile. This article which is formed of sheet metal, I designate by the numeral

5, and to illustrate the advantages of my improved method over others now in use, the article is fashioned or formed to provide a flat surface portion 6, and convex 5 surface portions 7 at opposite sides of said flat surface portion. This surface, so formed, is provided with a ground coat 8 of desired color or shade, depending on the hue of the wood it is desired to imitate, 10 unless the natural color of the surface of the article is suitable for the purpose; which, however, seldom occurs.

If the surface is suitable for the purpose intended, or when so prepared by applying 15 the proper ground coating for the same, it is stippled in any suitable way by applying thereto, irregular spatters 9 of paint of desired contrasting, preferably darker, color; the color, of course, being such as will accurately 20 match the color of the pores of the kind of wood to be imitated. Such spatters or paint regions are of varying areas and densities; the areas ranging from pin-point or infinitesimal areas to quite marked areas, 25 as clearly indicated in Figs. 2 and 3 of the drawing.

This irregular stippling effect may be produced in any suitable manner; but experiments have shown that the cleanest, 30 most effective, and quickest method of applying the same is by means of a spray gun; preferably operated under pressure; but any other method of applying the stippled paint to the article may be used.

35 A spray gun, however, operated under proper pressure, will most effectively apply the different size spatters or varied areas of paint in isolated regions, to assure a true simulation of the natural wood grain sought to be imitated, since it applies to the surface the finer and infinitesimal paint spatters or isolated regions of paint so necessary in simulating the finer grains or pores of the wood, as well as the varying large 45 and intermediate sizes of spatters or regions, from which the heavy wood pores and the coarser grain lines are respectively formed. The application of the various sizes, densities, and number of spatters may 50 be controlled by the length of time the spray gun is used in so applying the paint over any given surface. In simulating fine-grain wood, the formation of very heavy 55 spatters or isolated paint regions is not desired, and this is controlled by shortening the time intervals of so applying the paint.

For certain coarse grained wood, whether 60 straight grained, or otherwise, the paint is applied by means of the spray gun for longer periods of time, so that spatters or isolated paint regions will be enlarged in places by one spatter finding lodgement over or in overlapping relation to another; the effect of which will be presently explained. This effect may, of course, be se-

cured with a spray gun constructed or adjusted to assure the deposit of larger quantities of paint and heavier spatters.

The suitably colored surface which will lend the proper background, whether unprepared or prepared, when stippled or spattered with isolated paint specks or regions of varying sizes and densities, is given further treatment, while the stippled or spattered paint is still wet; and it may here be stated that the base or ground, which is the prepared or unprepared surface of an article before being stippled or paint spattered, should be of a shade or hue which approximates that of the wood to be imitated. For example, imitation of cherry or mahogany require a base or ground color of a shade approaching the red order, one of course lighter than the other; while oak and maple require a shade approaching yellow 85 and brown, respectively.

This explanation is not to be understood as limiting or restrictive in any sense, but is used herein to illustrate the need of varying colors or shades of colors when imitating different kinds of wood, which will be understood by those skilled in the art to which this invention relates.

While still wet, the paint spatters or isolated paint regions 9 of varying sizes are subjected to a spreading action, which may be effected by brushing the same in a straight-lined course, or substantially so, without guidance of a straight edge or similar device, since straight grained wood is more or less wavy in nature, such as would occur in attempting to spread or brush out the spatters or isolated paint regions in an unguided manner along a straight course.

In imitating certain kinds of woods, such as circassian walnut or other woods having a curled grain, the spreading of the spatters or paint regions may be effected by a straight-lined movement accompanied by a component circular or transverse movement 110 of the spreading medium.

Other kinds of wood may necessitate still different movements of the spreading medium; all of which will be understood by those skilled in this art.

It will be apparent that by spraying or otherwise applying the spatters or isolated paint regions on the article, particularly by force, under pressure or otherwise, such spatters or isolated paint regions will cover convex and relief surface portions of various kinds and enter concavities or depressed portions as readily as covering flat portions or surfaces. It is therefore of decided advantage to effect the spreading or elongating of the spatters or isolated paint regions by means of some device or medium which is conformable under pressure, such as is necessary to apply, to curved surfaces, whether convex or concave, and which is

also capable of entering depressed portions, or corners or angles of an article and effect a spreading or brushing-out of the spatters as thoroughly and completely as can be effected on flat surfaces.

With this in view, I prefer to employ a brush, such as shown at 10, Fig. 3, which has its bristles or other brushing or spreading elements 11, gradually lengthened from one end of the brush to the other; thereby providing a decidedly pointed end 12, which can be entered in depressions and crevices, and directed into corners or angular portions. That end of a brush so formed and having the long bristles or brushing elements can conform itself under proper pressure to concaved and convexed surface portions; and thus, articles of varied forms or sections can be treated alike, under my improved method, on all surface portions.

The brush 10 may have a suitable handle, such as 13, or otherwise; and in its movements over the stippled or irregularly spattered surface, will be directed as required to effect the desired markings.

It will, of course, be understood that the spread or brushed-out spatters of paint will, regardless of the manner of spreading or brushing, leave uncovered regions between the markings, lines or imitation pores so formed; such uncovered regions being exposures of portions of the base or ground color.

After simulating the graining of any wood in this manner, as indicated at 14, one or more coats of varnish or other finishing substances are applied and rubbed or otherwise treated in a manner well known.

Where, in the claims, the word "paint" is employed, it shall include any substance possessing the qualities to cover a surface or surface regions.

Having thus described my invention, what I claim is:—

1. The method of simulating the grain of natural wood on a metallic or other hard surface, which consists in irregularly spattering paint in varied sized regions over such surface, and before drying, spreading such paint regions to form elongated markings of varying degrees of fineness to simulate the pores of the wood to be imitated.

2. The method of simulating the grain of natural wood on a metallic or other hard surface, which consists in covering such surface with a ground coat of paint of or approximating the hue of the wood to be imitated, in then applying paint of a contrasting color to the ground coat by spattering the same to form comparatively small isolated paint regions of different densities and areas; and in then applying a suitable object to the paint-spattered surface and moving said object under pressure to spread the spatters and connect the paint of one with

another to create lines and elongated regions simulating the pores or grain of the wood being imitated.

3. The method of imitating wood grain, which consists in applying in an irregular manner to a ready metallic or other hard surface, spatters of paint of sizes varying from regions hardly discernible to comparatively large regions, and in working said spatters while wet into changed outlines or regions thinned out under such working to simulate pores or graining of wood.

4. In a method of simulating wood graining on a metallic or other hard surface having or prepared with the desired color of or approaching the hue of the wood to be imitated, the application of spatters of paint to such surface by directing the paint under force and through space in segregated and varying minute quantities, and in working said spatters while wet into changed outlines or regions thinned out by pressure applied under straight line movement accompanied by a component circular or transverse movement of the spreading medium.

In testimony whereof, I affix my signature.

GUSTAF ALBIN ROSE.
